UNITED STATES PATENT OFFICE.

IRVING L. KEITH, OF HAVERHILL, MASSACHUSETTS.

CEMENTING-MACHINE.

1,242,561.

Specification of Letters Patent.

Patented Oct. 9, 1917.

Application filed December 4, 1915. Serial No. 65,150.

To all whom it may concern:

Be it known that I, IRVING L. KEITH, a citizen of the United States, residing at Haverhill, in the county of Essex and State 5 of Massachusetts, have invented an Improvement in Cementing-Machines, of which the following is a specification.

This invention relates to certain improvements in cementing machines, and more particularly to improvements in machines for cementing cloth linings, or "doublers" for the vamps, or other parts of shoes, where it is desirable to have the cement applied in 10 dots, instead of over the entire surface.

While it is desirable that this work may be rapidly and thoroughly performed, it is particularly desirable that it be performed without applying any of the adhesive to the opposite side of the cloth from that to which 15 it is intended that the cement be applied, which undesirable result is liable to occur where the cloth is pressed onto a cementing surface by hand, as the hands of the operator are likely to become soiled, by coming in contact with said surface.

The object of my invention is to provide a form of cementing machine which is adapted to apply the cement in separate dots or patches to a sheet of textile, or other 30 flexible material, and which will perform this work thoroughly and rapidly and without danger of having the cement applied to the surface opposite the cemented surface.

I accomplish this object by the means 35 shown in the accompanying drawing, in which an embodiment of my invention is shown, and in which:—

Figure 1 is a sectional view, taken at the line 1—1 of Fig. 2, illustrating an embodiment of my invention.

Fig. 2 is a sectional view, taken at the line 2—2 of Fig. 1.

Fig. 3 is a detail view of a portion of the cement-applying roll.

Fig. 4 is a detail view, in section, of the edge portions of the cement-applying and press rolls.

As shown in the drawing, a suitably supported, cement-containing tank *a* is provided, in which a shaft *b* is mounted to rotate, and a series of wheels *c* are mounted on said shaft, each wheel being provided with a circular rim, from which a series of equally spaced, radially extending teeth 50 *d* project. Said wheels are spaced apart so that the spaces between the rims and the

spaces between the teeth of each rim are approximately the same, and the teeth are formed to taper slightly, and are provided with transverse faces *d'* at their ends, as 60 best shown in Fig. 2.

A cement-applying roll *e* is mounted on a shaft *f* directly above and in parallelism with the shaft *b*, the surface of said roll having a series of concentric ribs *e'* formed 65 thereon, which correspond in number to the number of rows of teeth on the shaft *b* and in diameter to the diameter of the path of the faces *d'* of teeth *d*, said ribs being arranged in rolling contact with said faces. 70

A press roll *g* is mounted on a shaft *h* directly over and in parallelism with the shaft *f*, and is provided with a series of concentric ribs *g'* which are mounted exactly midway of the ribs *e'* and therefore 75 directly over the spaces therebetween, said ribs *g'* being of substantially less width than the spaces between the ribs *e'*, and the peripheral diameter of said ribs *g'* being approximately the same as that of the 80 ribs *e'*.

Gear wheels *i*, *j*, and *k* are respectively mounted on the shafts *b*, *f*, and *h*, the pitch line of all of said gears being of the same diameter as the diameter of the work-engaging faces of the rolls *e*, *e*, and *g*, and a pulley *m* is mounted on the shaft *f*, so that the faces of said rolls may be simultaneously driven at the same surface speed. 85

A series of supporting wires *n* are horizontally arranged in parallelism, one to extend between each of the ribs *e'* directly beneath the ribs *g'* of the roll *g*, and out of contact therewith.

In practice, the tank *a* is filled with liquid cement to such a level that the end portions of the teeth *d* will dip therein, as shown in Fig. 1, so that when the machine is driven, a coating of cement will be applied to the end faces of said teeth. As each tooth is 95 separated from the other by an unobstructed space of substantial width, they become readily freed from surplus cement, which, although slowly flowing, will flow away from the end faces of the teeth, before they 100 come into contact with the ribs *e'*, with which they are arranged in rolling contact. As the machine is driven, a substantial portion of the cement remaining on the faces of the teeth will be applied in dots or 110 patches, to the surface of ribs *e*, as indicated in Fig. 2.

To perform the cementing operation, the operator places a sheet of the material, as *x*, to be cemented, on the wires *n* and slides it thereon in between the rolls *e* and *g*, so that the dots or patches of cement, which were applied to the ribs *e*, will be transferred to the material at the points where it comes in contact therewith. While the ribs *g'* do not press the material directly against the ribs *e'* they do so indirectly, as they press it down into the groove between said ribs *e'*, so that it is drawn over the surfaces of the ribs with sufficient force to cause firm engagement with the surface thereof, as particularly illustrated in Fig. 4. The application of the patches of cement to the material at all points at which it should be applied is thus assured. The material will be discharged from between the rolls onto the wires, where a second operator, preferably, may remove it and apply it to the piece to be reinforced.

The relative diameters, or positions of the work-engaging faces of the ribs *e'* and *g'* will be varied from the location shown, according to the thickness and flexibility of the material to be cemented. In no instance, however, is engagement of the faces of the ribs *g'* with the faces of the ribs *e'* possible, so that cement could be applied thereto, thus obviating all danger of having cement applied to the side of the material next the press roll.

With the above-described construction, the faces of the teeth *e* will always engage the same point on the faces of the ribs *e'*, so that cement will, at no time, be applied thereto at other than certain points, and continued application of the cement, to the same points, without having it removed by application to the work, will not cause the amount of cement applied to be increased to a material extent.

While the diameter of the path of movement of the faces of the teeth and the diameter of the faces of the ribs *e* are shown as the same, it will be apparent that these diameters may be varied, so long as they are arranged and driven in proportion so that the same points on the ribs will be successively engaged by the teeth.

I claim:

1. A cementing machine comprising a rotatably mounted roll having a series of circularly-arranged rows of radially-extending teeth thereon, said teeth having transverse faces at their ends arranged at uniform distances from the axis of the roll, and each row of teeth being spaced apart from the others, means to apply cement to said faces as the roll is rotated, and a second roll arranged to be held in pressing engagement with said first named roll and to be rotated in unison therewith.

2. A cementing machine, comprising a ro-

tatably mounted roll having a series of circularly-arranged rows of radially-extending teeth thereon, said teeth having transverse faces at their ends arranged at uniform distances from the axis of the roll, and each row of teeth being spaced apart from the others, a receptacle disposed beneath said roll into which the end-portions of said teeth dip, and a second roll arranged to be held in pressing engagement with said first named roll and to be rotated in unison therewith.

3. A cementing machine having a rotatably mounted, cement-applying roll, having a series of circularly-arranged rows of radially-extending teeth thereon, said teeth having transverse end faces at uniform distances from the axis of the roll, and each row of teeth being spaced apart from the others, means to hold liquid cement so that the ends of said teeth may dip therein when the roll is rotated, a cement-receiving roll arranged in rolling contact with said faces and means to hold the material to be cemented against said receiving-roll.

4. A cementing machine having a cement-applying roll comprising a series of circularly-arranged rows of radially-extending teeth, said teeth having end faces at uniform distances from the axis of the roll, and each row of teeth being spaced apart from the others, means to apply liquid cement to the ends of said teeth as the roll is rotated, a cement-receiving roll having a series of circular ribs respectively arranged with the peripheral faces thereof in rolling contact with the faces of said teeth, and a press roll having a series of circular ribs arranged opposite the spaces between the ribs of said receiving-roll to draw the material to be cemented against the said peripheral faces thereof.

5. A cementing machine having a cement-applying roll composed of a series of circularly-arranged rows of radially-extending teeth, said teeth having end faces at uniform distances from the axis of the roll, and each row of teeth being spaced apart from the others, means to hold liquid cement so that the ends of said teeth dip therein, when the roll is rotated, and a roll having circular, cement-receiving faces arranged and driven in rolling contact with the faces of said fingers, the circumferential length of said receiving faces and the length of the path in which the faces of said teeth travel corresponding, so that the faces of said teeth engage the same points on said receiving faces successively.

6. A cementing machine having a cement-applying roll composed of a series of circularly-arranged rows of radially-extending teeth, said teeth having end faces at uniform distances from the axis of the roll, and each row of teeth being spaced apart

from the others, means to apply liquid cement to the faces of said teeth when the roll is rotated, a roll having concentric cement-receiving ribs arranged in rolling contact with the faces of said fingers, a press roll having ribs opposite the grooves between said cement-receiving ribs for holding sheet material against said cement-receiving ribs, and a series of parallel, work-support-

ing wires extending between said cement-receiving ribs in position to support the material as it passes beneath said press roll.

In testimony whereof, I have signed my name to this specification.

IRVING L. KEITH.
